UNITED STATES PATENT OFFICE.

GEORGE H. RIVES, OF NEW YORK, N. Y.

LINING FOR PAILS.

1,209,207.

Specification of Letters Patent. Patented Dec. 19, 1916.

Application filed November 24, 1915. Serial No. 63,293.

To all whom it may concern:

Be it known that I, GEORGE H. RIVES, a citizen of the United States, and a resident of New York, county and State of New York, have invented a certain new and useful Improvement in Linings for Pails, of which the following is a full, clear, and exact specification.

This invention relates to a class of devices adapted to be used interiorly of pails, and has for its object primarily to provide a lining designed to be employed interiorly of a pail or like receptacle for receiving garbage and refuse to prevent the pail from being soiled, and which is formed so as to be adjusted to various diameters to allow the lining to be removably applied to receptacles of different sizes, the lining being made of paper, or other inexpensive material whereby it may be dispensed with when the receptacle is emptied of its contents.

The invention consists essentially of a hollow body composed of two interfitting sections each having an approximately semi-circular wall, or vertically disposed member, 25 and an integral substantially semi-circular bottom, or longitudinally disposed member, the bottom member of each section being slotted to provide two portions each preferably of substantially the shape of a quadrant for being adapted to be disposed in overlapping arrangement.

A further object of the invention is to provide a separate cover member also of paper, or other inexpensive material, having an aperture therein whereby the cover may be detachably applied to the lid of a pail as occasion may require.

A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing, Figure 1 is a vertical longitudinal section taken through one form of lining for pails embodying my invention, 50 the pail being shown in dotted lines, partly in detail, and partly in section. Fig. 2 is a top plan of a lid of the pail formed to permit the cover of the lining to be removably

mounted thereon. Fig. 3 is a view looking downwardly into the body of the lining 55 when its parts are assembled. Fig. 4 is a section taken on the line IV—IV of Fig. 1, and Fig. 5 is a top view looking downwardly into one of the interfitting sections of the lining.

The device, or lining has a hollow body 10 composed of two sections, as 11 and 12, which may be made of paper, or other comparatively inexpensive material so as to be dispensed with after being once used. The 65 sections 11 and 12 are preferably similar in formation, and each section has a wall, or vertically disposed member 13 of substantially a semi-circular shape. The wall member of one of the sections is curved on a 70 slightly less radius than the wall member of the other section so that the smaller section may interfit the other section, in order to allow the circumference of the body to be varied when the lining is in use, as will be 75 hereinafter more fully explained.

Formed integrally with the lower end of the wall member 13 of each of the sections 11 and 12 of the body is a bottom, or longitudinally disposed member 14, and both of 80 these bottom members are substantially semi-circular in shape. Each of the bottom members 14 is transversely slotted, at 15, to provide two portions 16 and 17 each preferably of substantially the shape of a quadrant for 85 being adapted to be disposed in overlapping arrangement, as indicated in Figs. 3, 4, 5, whereby the diameter of the bottom of the body may be reduced when the sections 11 and 12 are assembled and applied interiorly 90 of a receptacle, such as a garbage pail, as at 18, Fig. 1, having a tapered wall.

On the upper edge of the wall member 13 of each of the sections of the body 10 may be a semi-circular flange 19, and both of 95 these flanges are arranged to overhang the exterior of the wall member so as to lap over the upper edge of the wall of the pail. In conjunction with the sectional body 10 of the lining, I may also provide a cover member, as 20, adapted to be removably applied interiorly of the lid, as 21, of the pail, this lid being provided with a knob, or handle, as 22, which is rotatably disposed through an opening centrally of the lid, and on the 105 lower end of this handle is a clip preferably

in the form of a projecting finger, or lug 23 adapted to be swung circumferentially in slightly spaced relation to the underside of the lid of the pail. The cover member 20 has a circular flat body part 24 which may be of a size to fit interiorly of the lid of the pail, and on the outer edge of this body part is a downwardly extending flange, as 25, adapted to lay against the depending flange 10 of the lid of the pail, while centrally of the cover member is an elongated opening 26 for reception of the finger 23 of the handle of the lid of the pail.

When the lining is applied to a garbage pail the larger semi-circular section of its body 10 is first fitted in the body of the pail so as to be disposed against part of its wall and so that the bottom member 13 of this section will rest upon the bottom of the pail. If required the two portions 16 and 17 of the bottom member 14 may be arranged to overlap each other so that the bottom member will conform with the size of part of the bottom of the pail, and the smaller semi-circular section of the body of the lining is similarly fitted in the body of the pail at an opposed part to the first section. If the circumference of the sections of the body of the lining when thus applied to the body of the pail is greater than the interior of the pail the smaller section of the body of the lining is arranged so that its edges will overlap the larger section, as illustrated, and the flanges 19 of the sections 13 are arranged to overhang the upper edge of the body of the pail. When the cover member 20 is used on a pail it is applied on the underside of the lid, and the knob, or handle 22 is revolved so that the finger 23 will be inserted through the opening 26 of the cover member. By then rotatably moving the handle accordingly the finger 23 will engage a part of the cover member adjacent to its opening, and the cover member will be removably held to the lid of the pail so that the flange 25 will overlap the flange of the body 10 of the lining, though in instances the cover member may be dispensed with. When the lining is applied to a pail in this manner garbage and other refuse may be received in the body 10 of the lining, and with the emptying of the contents of the pail the lining is also dispensed with, thereby preventing the pail from being soiled. Moreover, by making the lining in two interfitting sections, as described, the device may be manufactured in uniform sizes, and adjustably applied to pails of various diameters.

In the foregoing description, I have embodied the preferred form of my invention, but I do not wish to be understood as limiting myself thereto, as I am aware that modifications may be made therein without departing from the principle, or sacrificing any of the advantages of this invention,

therefore I reserve to myself the right to make such changes as fairly fall within the scope thereof.

Having thus described my invention, I claim as new and desire to secure by Letters Patent:—

1. In a lining for receptacles, a hollow body composed of two sections each having a bottom member and one of the sections being larger than the other so that the sections will interfit when assembled as well as permitting the lining to be adjusted to various diameters to fit receptacles of different sizes, substantially as set forth and for the purpose specified. 30

2. In a lining for receptacles, a hollow body composed of two sections each with a substantially semi-circular wall member having on its top edge an outwardly extending overhanging flange, and having on its lower edge a bottom member, and one of the sections being larger than the other so that the sections will interfit when assembled as well as permitting the lining to be adjusted to various diameters to fit receptacles of different sizes, substantially as set forth and for the purpose specified. 90

3. In a lining for receptacles, a hollow body composed of two sections each with a vertically disposed substantially semi-circular wall member, and having a longitudinally disposed substantially semi-circular bottom member, the bottom member of each section being slotted to provide two portions for being disposed in overlapping arrangement, and one of the sections being larger than the other so that the sections will interfit when assembled as well as permitting the lining to be adjusted to various diameters to fit receptacles of different sizes, substantially as set forth and for the purpose specified. 100

4. In a lining for receptacles, a hollow body composed of two sections each with a substantially semi-circular wall member having on its top edge an outwardly extending overhanging flange, and having on its lower edge a bottom member, and one of the sections being larger than the other so that the sections will interfit when assembled as well as permitting the lining to be adjusted to various diameters to fit receptacles of different sizes, and a separate cover member for the lining, formed so as to be removably applied to the lid of the receptacle. 110

5. In a lining for receptacles, a hollow body composed of two sections each with a vertically disposed substantially semi-circular wall member, and having a longitudinally disposed substantially semi-circular bottom member, the bottom member of each section being slotted to provide two portions for being disposed in overlapping arrangement, and one of the sections being larger than the other so that the sections will inter- 125 130

fit when assembled as well as permitting the lining to be adjusted to various diameters to fit receptacles of different sizes, and a separate cover member for the lining, said cover member having a downwardly projecting flange for encompassing the top of the lining.

This specification signed and witnessed this twenty third day of November, A. D. 1915.
